ELECTRIC ARC LAMP

George J. Anderson, Hollywood, Calif., assignor to
 Warner Bros. Pictures, Inc., New York, N. Y., a
 corporation of Delaware

Application September 18, 1939, Serial No. 295,472

8 Claims. (Cl. 176—51)

This invention relates to electric arc apparatus and has particular reference to electric arc lamps.

One object of the invention is to accurately control the feeding of the electrodes of an arc lamp toward each other to compensate for the burning away of the tips thereof.

Another object is to maintain correct relative feeding movement of a pair of electrodes toward each other and to enable such relative feeding movement to be varied as desired, with or without varying the rotation of one of the electrodes.

Another object is to provide for selective, automatic, or manual feed of an electrode for an electric arc apparatus.

Another object is to enable quick removal of an electrode feeding apparatus from its housing, as a unit, for replacement or repair.

Another object is to facilitate focusing an electric arc lamp.

A still further object is to simplify the construction of an electric arc lamp.

In certain fields employing electric arc lamps, particularly the motion picture industry, it is necessary to maintain the intensity of an arc in an arc lamp at as uniform a brilliancy as possible, so as to provide an unflickering beam of light. To produce this unflickering illumination, one of the electrodes, generally the positive, is caused to be rotated about its axis at a steady rate, while being fed longitudinally, so as to uniformly burn, or form a symmetrical crater, at the tip of that electrode.

The present invention contemplates a simplified drive assembly for rotating one of the electrodes, i. e., the positive, and for feeding the electrodes at desired relative longitudinal speeds, while enabling regulation of these relative speeds, independently of the rate of rotation of the rotated electrode.

Thus, the arc apparatus may be regulated to accommodate electrodes having different burning rates, and may also be regulated to compensate for a varying current supply for the electrodes while being capable of feeding the same at such a speed as to maintain a maximum of brilliancy and uniformity of illumination. This latter feature is of considerable importance in the motion picture industry, where, in the photographing of sets or scenes, large numbers of arc lamps are usually employed. Many of these lamps are turned off and on at different times, thus greatly changing the load conditions of the current supply and consequently affecting a noticeable change in voltage. This is particularly true in cases where portable generating equipment of

relatively small capacity is employed; for example, in motion picture production on location, or in an emergency where it is not possible to obtain current from a main source of supply.

5 The invention further contemplates the quick and ready removal of the electrode feeding apparatus, as a unit, from its housing to facilitate repair or replacement of that unit. This feature is also of considerable importance in the motion picture industry where the loss of time incurred due to repair or replacement of any equipment is very costly.

The manner in which the above and other objects of the invention are accomplished will be readily apparent from the following specification, when read in conjunction with the accompanying drawings, wherein:

Fig. 1 is a longitudinal sectional view of an electric arc lamp and housing therefor, embodying the present invention.

Fig. 2 is a transverse sectional view through the electric arc apparatus and housing therefor, and is taken along the line 2—2 of Fig. 1.

Fig. 3 is a sectional plan view of the rear panel and part of the arc lamp housing and is taken along the lines 3—3 of Fig. 1.

Fig. 4 is a sectional plan view of the intermittent driving mechanism for the negative electrode feeding head and is taken along the line 4—4 of Fig. 2.

Fig. 5 is a transverse sectional view through the intermittent drive and is taken along the line 5—5 of Fig. 4.

Fig. 6 is a transverse sectional view through the feeding mechanism for the negative electrode and is taken along the line 6—6 of Fig. 1.

Fig. 7 is a longitudinal sectional view through the positive electrode feeding head and is taken substantially along the line 7—7 of Fig. 2.

Fig. 8 is a transverse sectional view through the positive electrode feeding head and is taken along the line 8—8 of Fig. 7.

Fig. 9 is a transverse sectional view through the feed gears and support therefor in the positive electrode feeding head, and is taken along the line 9—9 of Fig. 7.

Fig. 10 is a sectional view through the positive electrode head illustrating particularly the manual feed drive therefor, and is taken along line 10—10 of Fig. 8.

Fig. 11 is a transverse sectional view through the combined contact brush and heat shield unit for the positive electrode feeding head, and is taken along the line 11—11 of Fig. 7.

55 Referring in particular to Fig. 1 and Fig. 2,

the electric arc lamp assembly comprises a box-shaped housing 10, open at the top thereof and having baffle plates 12 and 13 extending across the top thereof to form a light seal while permitting a draft of air to be passed therethrough. Openings as at 14, 15, 16 and 17 are formed in the lower portion of the walls of the housing 10 to permit air to be passed upwardly therethrough for cooling purposes. The front wall 18 of housing 10 has an opening therein surrounded by a substantially cylindrical flange 19 in which is secured a lens 20 of the Fresnel type. The rear wall 21 of the housing 10 has a rectangular opening 22 therein, normally closed by a rear cover member, or panel 23, which is removably secured to the wall 21 by screws 24.

The electrode feeding assembly comprises a positive electrode feeding device or head generally indicated at 25 for feeding a positive electrode or carbon A, and a negative electrode feeding device or head generally indicated at 26 for feeding a negative electrode or carbon B. Both heads 25 and 26 are supported by a base 27, to the under surface of which is secured a drive motor 28 for the purpose of driving the electrode feeding mechanism in each head.

The base 27 has a pair of spaced ears, as at 29 and 30, extending from opposite sides thereof. These ears, as at 29 and 30, have bearings formed therein and are movable along a pair of spaced parallel rods 31 and 32 extending from the front wall 18 to the rear wall 21 of the housing 10.

One of the rods 31 is screw threaded at 33 and is journaled at the front end thereof in a bearing 34 provided in the front housing wall 18. The rear end of rod 31 is journaled in a bearing 35 provided in the panel 23. A handle 36 is secured on the end of rod 31 extending through bearing 35, whereby to enable manual rotation of the rod 31. The bearing 35 and rear end of rod 31 are so formed as to prevent endwise movement of rod 31 relative to panel 23.

As will be noted in Fig. 1, ear 30 on base 27 is screw-threaded and mounted on the threaded portion 33 of rod 31, whereby to cause movement of the entire electrode feeding assembly toward and away from lens 20 on rotation of the handle 36. That is, rotation of the handle 36 will cause movement of the arc produced across the tips of the positive electrode A and the negative electrode B into or out of the focus of the lens 20.

As shown in Fig. 3, the rod 32 is secured at 38 to the rear panel 23, and is slidably received at the front end thereof in a bearing (not shown) similar to that of 34 and mounted or formed on the front wall 18 of the housing 10.

The positive electrode feeding head 25 is mounted on a sub-base 39 which is supported by posts 52 and 52' from the main base 27. A layer 39' of insulating material, such as asbestos or the like, is interposed between the head 25 and the base 39 to electrically insulate this head.

Describing in detail the positive head 25, reference is had to Figs. 7, 8, 9, 10, and 11, inclusive. Head 25 comprises a cylindrical housing 40, having legs 41 (Figs. 1 and 2) at the bottom thereof, which are secured by bolts 42 to the sub-base 39. Bolts 42 pass through suitable insulating bushings (not shown). The housing 40 has an apertured end wall 43 at the forward end thereof, and is open at the rear thereof, there being a cylindrical shoulder 44 formed thereon and adapted to snugly receive a mating cylin-

drical portion of a casing 45. Casing 45 is open at the end thereof adjacent housing 40 and is removably secured to this housing by screws 46. Housing 40 and casing 45 form a substantially enclosed compartment to house the electrode feeding mechanism.

A bearing counterbore 47 is formed at the rear of the casing 45 to receive a ballbearing assembly 48. A cap 49, having a centrally located electrode receiving aperture 50 therein, is secured to the end of casing 45 by screws 51, to retain the bearing assembly 48 in the counterbore 47 and prevent longitudinal movement thereof.

An electrode carrier generally indicated at 53 is rotatably supported by the bearing assembly 48. Carrier 53 comprises a tubular member 54, having a longitudinally extending bore therethrough, to loosely receive the positive electrode A. A crown gear member 55 is slidably fitted over the member 54, and abuts a shoulder 56 formed on member 54.

A lock nut 57 threaded on the rear end of the member 54 is provided to secure the gear member 55 to the tubular member 54, and also to lock the member 54 in the bearing assembly 48, to prevent longitudinal movement thereof.

Referring in particular to Figs. 7 and 9, it will be noted that the forward portion of the tubular member 54 is formed into an enlarged head 58 having a longitudinally extending slot 59 formed therein. A pair of diametrically opposed, transversely extending grooves, 60 and 61, are cut into the head 58, to receive and guide a pair of stub shafts 62 and 63 therein, respectively. A pair of feed gears, or wheels, 64 and 65 are journaled on the stub shafts 62 and 63, respectively. Gears 64 and 65 are located in and guided against longitudinal movement by the opposed sides of the groove 58. A pair of tension springs 66 and 66' are provided between the ends of the stub shafts 62 and 63, to resiliently urge the teeth of the gears 64 and 65 into driving engagement with the surface of the positive electrode A. A spiral or scroll gear member 67 is journaled on a bearing portion formed on the tubular member 54, directly behind the head 58, and has a set of spiral gear teeth 68 formed on one face thereof which mesh with the teeth of the gripper gears 64 and 65. From the above it will be noted that relative rotation of the tubular member 54 and spiral gear member 67 will cause rotation of the gears 64 and 65 about their respective shafts, to impart a longitudinal feeding movement of the positive electrode A.

A set of spur gear teeth 69 are formed on a periphery of gear 67.

Referring in particular to Figs 7 and 8, a three-lobed cam 70 is secured to the face of the crown gear member 55, intermediate gears 55 and 67 by screws, one of which is shown at 71. A cam follower 72 rides on the surface of cam 70 and is reciprocal in a guide block 73 which extends through an opening formed in the casing 45 and is secured to this casing by screws, as at 74. That is, cam follower 72 is slidable, in a substantially vertical direction, in a bearing formed in block 73. A compression spring 75 is interposed between the cam follower 72 and the block 73 to resiliently urge the follower 72 into engagement with the cam 70.

A portion of the cam follower 72 extends through the top of the guide block 73 and has a stop screw 76 screw threaded therethrough. The bottom end of screw 76 has a conical point formed thereon and adapted to engage any one

of the teeth 69 on gear 67, when the cam follower 72 rides upon a flattened portion 78 of cam 70. From the above it will be noted that on rotation of the tubular member 54, the positive electrode A will be rotated and the cam follower 72 will be reciprocated three times per revolution of the member 54. As the cam follower 72 moves downwardly, the conical point of screw 76 engages a tooth on the periphery of the spiral gear member 67, thereby arresting rotation of this member, and, due to the relative rotation between the head 58 and the gear 67, will effect rotation of the gears 64 and 65 to cause feeding movement of the electrode A. In other words, a feeding movement will be imparted to the electrode A three times per revolution of the electrode carrier 53.

In the event that it is desired to regulate the rate of feeding of the electrode A independently of the rate of rotation thereof, a lock nut 79, threaded on screw 76 and abutting the upwardly extending portion of the cam follower 72, is loosened, allowing the screw 76 to be raised or lowered, whereby the interval of time during which the conical point of screw 76 is engaged with one of the teeth 69 may be regulated, which of course will regulate the amount of each feeding impulse. That is, if the screw 76 is lowered, the conical point of this screw will engage a tooth 69 at an earlier moment on the downward travel of the cam follower 72 and will be disengaged from that tooth at a later moment, thus holding the gear 67 in a fixed position for a longer period of time. Since each feeding impulse of the electrode is of considerable duration, but causes only a very short length of travel, and, furthermore, since there are a plurality of impulses for each rotation of the electrode, it will be noted that the slight unevenness of longitudinal feeding travel will be insufficient to cause a flicker or change in the illumination of the arc.

The above mentioned positive electrode feeding head 25 is described and claimed in my Patent No. 2,173,149 granted September 19, 1939, for Electrode feeding device for electric arc apparatus. However, in that patent, a series of serrations are provided around the periphery of the gear 67, in lieu of the gear teeth 69.

Referring to Figs. 1, 8 and 10, the electrode A is adapted to be manually fed in a longitudinal direction, independently of the motor drive for the two electrode feeding heads 25 and 26, by a shaft 80 which extends rearwardly from the casing 45 through a hole formed in panel 23 and terminates in a handle 81. Shaft 80 is divided into two sections which are connected together, and insulated from each other, by a coupling 82 of insulating material, such as bakelite. The inner end of shaft 80 is journaled in a bearing 83 formed in the casing 45. A pinion 84 is secured to the inner end of the shaft 80 and is adapted to mesh with the gear teeth 69 formed on the gear member 67, but is normally out of engagement therewith. When it is desired to manually feed the electrode A; as, for example, when inserting a new electrode or when moving the electrode into a correct alignment with the negative electrode B; the handle 81 is pressed inwardly against the action of a compression spring 85, interposed between the casing 45 and the coupling 82. This action causes the gear 84 to move into mesh with the gear teeth 69, and, on rotation of the handle 81, the spiral gear 67 will be rotated relative to the head 58, to impart a feeding motion to the feed gears 64 and 65.

Due to the fact that the shaft 80 extends a considerable distance behind the panel 23, it will be noted that the handle 81 will not interfere with the focusing adjustment of the electrode feeding assembly.

Included in the positive head 25 is a combination contact brush and shield assembly, generally indicated at 87, which is situated in front of the housing 40 to shield the electrode feeding mechanism of the positive head 25 from the intense heat of the arc produced across the electrodes A and B. This assembly comprises a member 88 secured, as by screws 89, to the sub-base 39 through the insulating layer 39'. Note that member 88 does not touch the housing 40, thereby permitting an insulating layer of air to extend therebetween. Member 88 has an electrode receiving aperture extending centrally therethrough, through which electrode A passes. A shield unit is secured in front of member 88 and comprises, in part, a metal plate 90, secured by screws 91 to the front face of the member 88. An asbestos plate 92 and a metal plate 93 separated from the plate 92 by the spacers 94 are secured to the plate 93 by screws 95. A horizontally extending channel 96 is provided in the front face of the member 88 and has a stationary contact shoe 97, secured therein by a lock screw 98 (Figs. 7 and 11). Screw 98 passes through an elongated slot 99, formed in shoe 97, whereby this shoe may be moved into different positions and then locked. The inner end of the shoe 97 is concave to fit the surface of the electrode A. Also mounted in the channel 96 is a spring-pressed movable contact shoe 100, also having its inner end concave to fit the surface of the electrode A.

Current is supplied to the movable contact shoe 100 by a flexible conductor 101 which is secured in a terminal clip 102. Clip 102 is secured to the end of contact shoe 100 by a bolt 103, the head of which is engaged by a lever 104 pivoted at 105 to brackets 106 extending from the member 88. The opposite end of lever 104 is engaged by a compression spring 107 (Fig. 2).

The negative electrode feeding head 26 comprises an electrode clamp 109 secured to the negative electrode B and slidable along a pair of spaced guide rods 110 and 111 (Fig. 6). Rods 110 and 111 are secured at their opposite ends in brackets 112 and 113 extending from a continuation of the sub-base 39. A screw threaded shaft 114 extends parallel to the electrode B, intermediate rods 110 and 111 and is suitably journaled at opposite ends thereof, in bearings formed in the brackets 112 and 113. Shaft 114 is also slidable lengthwise a limited amount in its bearings.

A tooth 115, mounted on a lever 116 (Fig. 6), is carried by the clamp 109 and is normally in engagement with the threads of shaft 114, thereby forming a travelling nut member. Lever 116 is pivoted at 117 to a depending portion of the clamp 109 and is spring pressed in a clockwise direction to cause the tooth 115 to engage the shaft 114 by a spring 118. By depressing the lever 116, the tooth 115 will be moved out of engagement with the shaft 114, thereby enabling the clamp 109 to be moved along the rods 110 and 111, enabling the adjustment of the electrode B toward or away from the electrode A. A bevel gear 120 is slidably keyed on the screw threaded shaft 114 at the upper end thereof and is maintained in continual mesh

with a mating bevel gear 121 fixed to the end of a negative drive shaft 122. The above mentioned description of the details of the clamp 109, as well as the provision for allowing the screw 144 to be moved lengthwise for striking the arc, is not a subject of the present application and it is therefore not believed necessary to describe the same in further detail.

Shaft 122 is journaled in bearings 123 and 124 formed on the sub-base 39. The end of shaft 122 extends through the hole in panel 23 and terminates in a handle 125, to enable manual feeding operation of the electrode B independent of the motor drive therefor. Shaft 122 is divided into two sections which are insulated from each other by a coupling 126 of Bakelite or other insulating material.

Referring in particular to Fig. 2, the motor 28 has a gear reduction unit (not shown) provided in a housing 127 formed at one end bell of the motor. This gear reduction unit is connected to and drives a main drive shaft 129, which is journaled at the upper end thereof (Fig. 7) in a bearing 130 formed in the casing 45. A bevel pinion 131 is formed on the upper end of shaft 129 and meshes with the crown gear 55 to drive the electrode feeding mechanism of the positive head. Shaft 129 is divided into two sections which are connected together and insulated from each other by a coupling 130 of Bakelite or like material.

A worm 131 (Figs. 4 and 5) is secured to shaft 129 intermediate its ends and meshes with a worm gear 132 loosely journaled on a sleeve 133 which is secured to the negative drive shaft 122. Worm gear 132 is maintained in engagement with a flange 134 on the sleeve 133 by a compression spring 135, these members, (the flange 134 and gear 132), forming the coacting elements of a friction clutch, to enable a non-positive drive connection between the worm gear 132 and shaft 122 to be maintained. A lock nut 137 is threaded on the end of sleeve 133 to retain the spring 135 under compression and is adjustable along the sleeve 133 to vary the friction between the gear 132 and sleeve 133.

A three-lobed cam 133 is secured, in a suitable manner, to the worm gear 132 and is engaged by a cam follower 139 slidably mounted in a guide block 140. Block 140 is suitably secured to, and extends through, an opening formed in a protective housing 141 which surrounds the worm 131 and gear 132 and protects the same from carbon dust and the like. Housing 141 is secured through the base 27, as by screws 142.

Cam follower 139 is similar to that of 12, there being a compression spring 143 interposed between this cam follower and a well, formed in the guide block 140, to resiliently press the cam follower in engagement with the cam 138. A stop screw 144 is threaded through the cam follower 139 and is adapted to be adjustably locked in different positions by a lock nut 145 threaded thereon. The inner end of screw 144 is pointed and is adapted to engage any one of a plurality of serrations provided on the periphery of a member 146. Member 146 is interposed between the gear 132 and the compression spring 135 and is slidably keyed to the sleeve 133 by means of a pin 147. Thus, member 146 forms another element of the aforementioned friction clutch. From the above, it will be noted that on rotation of the worm gear 132 by the worm 131 on the main drive shaft 129, the cam 138

will reciprocate the cam follower 139 and, consequently, the stop screw 144, which will intermittently engage the serrated member 146 to arrest the rotation of the negative drive shaft 122. Adjustment of the stop screw 144 will act to change the period during which the serrated member 146 and, consequently, the feeding of the negative electrode B is maintained in a manner similar to that described in connection with the stop screw 16.

By arranging the motor 28 to one side of the vertical plane passing through the positive electrode A and the negative drive shaft 122, and by inclining the main drive shaft 29, as indicated in Fig. 2, a simplified drive connection between the shaft 129 and the negative feeding mechanism of the head 26 is obtained. This results in a minimum number of gears and other rotating parts to effect quiet operation as well as a simple and economically manufactured driving mechanism.

In order to automatically strike the arc between the electrodes A and B, an electro-magnet 149 is provided for this purpose. This electro-magnet 149 is connected in series with the circuit through the electrodes A and B, and is supported on a metallic L-shaped base 150 which is suspended by means of brackets or posts 151 from the bottom of the base 27. A metal armature 152 is pivoted at 153 to the base 150 and is held in the position illustrated in Fig. 1, when no current is being passed to the arc lamp, by a tension spring 154, extending between the armature 152 and the ear 29 of base 27. Armature 152 is pivotally connected to one end of a link 155 which, in turn, is pivotally connected to one end of a bell crank lever 156. Lever 156 is pivoted at 157 to the lower end of the sub-base 39 and has the other end thereof extending through an aperture 157' in sub-base 139, and formed into a yoke (not shown) which engages a groove 158 formed in the threaded shaft 114. Shaft 114 is reciprocal longitudinally thereof by the bell crank 156 to move the clamp 109 and electrode B from the striking position illustrated in Fig. 1 to an operating position (not shown). This type of strike mechanism, i. e., the slidable rod 114 and bell crank 156, is well known in the art and it is therefore not deemed necessary to describe same in further detail.

Bearing in mind the above description of the arc striking mechanism, and assuming that the electrodes have been correctly positioned so that they will contact each other in striking position, it will be noted that when current is first passed through the lamp circuit, contact will be made across the tips of the electrodes to complete this lamp circuit. Soon after the establishment of the circuit across the electrodes the electro-magnet 149 will become effective to actuate the armature 152. Thus, the negative electrode B will be drawn downwardly a predetermined distance to separate the tip thereof a desired distance from the tip of the electrode A to produce the arc.

A rheostat indicated at 159 is suitably secured to the inner surface of the panel 23 and is connected in the circuit of motor 28 to enable the speed thereof to be regulated. A control knob 160, extending on the exterior panel 23, enables adjustment of rheostat 159.

The procedure which may be followed in regulating the electrode feeding mechanism is to maintain the motor 28 at a constant speed, whereby to maintain the rotation of electrode A con-

stant, and to adjust the stop screws 76 and 144 to regulate the feeding movements of the electrodes A and B respectively, as desired. However, regulation of the feeding movements may be obtained by merely regulating the speed of the motor 28 by the rheostat 159. Another alternative method of regulating the feeding speeds of the electrodes is to back off, or entirely remove, the stop screw 144, so as to enable the same to be ineffective to arrest the rotation of the negative drive shaft 122. In this case, the speed of the motor 28 may be regulated to obtain the correct feeding speed of the negative electrode B, while adjusting the stop screw 76 to obtain the correct feeding speed of the positive electrode A.

When it is desired to remove the electrode feeding assembly, including the positive head 25 and negative head 26, from the housing 10, for replacement or repair, flexible conductors 162, extending between a suitable socket on the bottom of the housing 10 and a terminal block 163 on the base 27, are removed. The screws 24, securing the panel 23 to the rear wall 21 of the housing 10, are then removed, enabling the panel 23 to be moved rearwardly, carrying the rods 31 and 32, as well as the entire electrode feeding unit and motor 28, out of the housing 10. It will be seen that the entire assembly is then completely detached from housing 10. Since the forward ends of the rods 31 and 32 are merely fitted in bearings at the forward wall 18 of the housing 10, no further disconnecting of any of the supporting members of the electrode feeding assembly is required.

Although the invention has been described in connection with, and is particularly applicable to, a lens type housing, it is to be understood that with certain obvious modifications, the apparatus of the invention may be applied to a reflective type housing. For example, the opening 22 and the panel 23 covered thereby may be extended upwardly and a reflector may be secured to the panel 23.

Having thus described the invention, what is claimed as new and desired to secure by Letters Patent is.

I claim:

1. Electric arc apparatus comprising the combination of a positive electrode feeding device, a negative electrode feeding device, a drive shaft for driving one of said devices, means for rotating said shaft, a shaft for driving the other of said devices, a frictional clutch operatively connecting said last mentioned shaft to said first mentioned shaft for driving said other device, and means actuated by said first shaft for intermittently rendering said clutch inoperative to drive said other shaft.

2. Electric arc apparatus according to claim 1, comprising adjustable means for controlling said last mentioned means to vary the period during which said clutch is rendered inoperative.

3. Electric arc apparatus comprising the combination of an electrode feeding device, a drive shaft for said device, a drive member rotatably mounted on said shaft, a frictional drive connection between said member and said shaft, means for rotating said member, and means actuated by

said member for intermittently operating said frictional drive connection for arresting the rotation of said drive shaft.

4. Electric arc apparatus comprising the combination of an electrode feeding device, a drive shaft for said device, a member rotatably mounted on said shaft, a frictional drive connection between said member and said shaft, a cam operatively connected to said member, a cam follower movable by said cam, a stop member operable by said cam follower and adapted to arrest the rotation of said shaft on movement of said cam follower by said shaft, and means for rotating said member.

5. Electric arc apparatus according to claim 4, comprising an adjustable connection between said cam follower and said stop member whereby the period during which said shaft is arrested by said stop member may be varied.

6. Electric arc apparatus comprising the combination of an electrode feeding device, a drive shaft for said device, means on said shaft forming a clutch element, a drive member rotatably carried by said shaft and forming a second clutch element adapted to engage said first mentioned clutch element to form a driving connection with said shaft, a cam operatively connected to said drive member, a serrated member slidably keyed to said shaft adjacent said drive member and on the side thereof opposite said first mentioned clutch element, means for resiliently urging said serrated member against said drive member to effect a drive connection between said drive member and said shaft, means for rotating said drive member, and means actuated by said cam for periodically arresting the rotation of said serrated member.

7. Electric arc apparatus comprising the combination of a positive electrode feeding head, a negative electrode feeding head, a drive shaft for said positive head, means for rotating said drive shaft, a second drive shaft for said negative head, a gear operatively connected to said first mentioned shaft, a second gear rotatably mounted on said second shaft and meshing with said first mentioned gear, means forming a frictional drive connection between said second gear and said second shaft, and means comprising a cam on said second gear for periodically interrupting the rotation of said second shaft.

8. Electric arc apparatus comprising the combination of a base, negative and positive electrode feeding heads on said base, a motor on said base, a substantially horizontally extending drive shaft terminating at said negative head, the axes of said positive head and said motor extending horizontally substantially parallel to said negative drive shaft with the axis of said positive head and the axis of said negative drive shaft in substantially the same vertical plane and with the axis of said motor offset to one side of said plane, and a substantially straight shaft extending from said motor to said positive head at one side of said negative drive shaft and a worm on said substantially straight shaft and a cooperating worm wheel on said negative drive shaft.

GEORGE J. ANDERSON.
